Primary Examiner—Cathron C. Brooks*Assistant Examiner*—Austin Murphy(74) *Attorney, Agent, or Firm*—Mehul R. Jani; Adan Ayala; Charles Yocum(57) **CLAIM**

The ornamental design for an angle grinder, as shown and described.

DESCRIPTION

FIG. 1 is a perspective view of an angle grinder showing the new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines shown in the drawings form no part of the claimed design.
